(57) **CLAIM**

The ornamental design for a connector having two identical members, as shown and described.

DESCRIPTION

FIG. 1 is perspective view of one of two identical members of the connector having two identical members in an opened position.

FIG. 2 is a first side view of the one identical member of the connector having two identical members of FIG. 1.

FIG. 3 is a second side view of the one identical member of the connector having two identical members of FIG. 1.

FIG. 4 is first end view of the one identical member of the connector having two identical members of FIG. 1.

FIG. 5 is a second end view of the one identical member of the connector having two identical members of FIG. 1.

FIG. 6 is top view of the one identical member of the connector having two identical members of FIG. 1.

FIG. 7 is a bottom view of the one identical member of the connector having two identical members of FIG. 1.

FIG. 8 is a perspective view of one identical member of the connector having two identical members in a closed position.

FIG. 9 is a first side view of the one identical member of the connector having two identical members of FIG. 8.

FIG. 10 is a second side view of the one identical member of the connector having two identical members of FIG. 8.

FIG. 11 is a first end view of the one identical member of the connector having two identical members of FIG. 8.

FIG. 12 is a second end view of the one identical member of the connector having two identical members of FIG. 8.

FIG. 13 is a top view of the one identical member of the connector having two identical members of FIG. 8.

FIG. 14 is a bottom view of the one identical member of the connector having two identical members of FIG. 8.

FIG. 15 is a perspective view of both members of the connector having two identical members joined together and in an opened position, oriented towards each other.

(Continued)

FIG. 16 is a perspective view of both members of the connector having two identical members joined together and in an opened position, oriented away from each other.

FIG. 17 is a perspective view of both members of the connector having two identical members joined together and in a closed position, oriented toward each other; and,

FIG. 18 is a perspective view of both members of the connector having two identical members joined together and in a closed position, oriented away from each other.
